UNITED STATES PATENT OFFICE.

FREDRICK NEUDORFF, OF SHEFFIELD, ALABAMA, ASSIGNOR, BY MESNE ASSIGNMENTS, TO MEMPHIS COLUMN COMPANY, OF MEMPHIS, TENNESSEE, A CORPORATION OF MICHIGAN.

TURNING-LATHE.

No. 828,897.

Specification of Letters Patent.

Patented Aug. 21, 1906.

Application filed August 2, 1905. Serial No. 272,367.

To all whom it may concern:

Be it known that I, FREDRICK NEUDORFF, a citizen of the United States, residing at Sheffield, in the county of Colbert, State of Alabama, have invented certain new and useful Improvements in Turning-Lathes, of which the following is a specification, reference being had therein to the accompanying drawings.

This invention relates to a turning-lathe, and particularly to a structure suitable for producing columns and other wooden objects having a circular configuration.

The invention has for an object to improve the construction and arrangement of the parts whereby the object to be turned shall travel laterally of a relatively fixed cutter, both of said parts being rotated during said movement, and means provided whereby the travel of the work-holder is automatically reversed at its opposite extremes.

A further object of the invention is to provide a novel and improved construction of back cutter-knife adapted to reciprocate upon the standards of the machine and also to carry upon its frame cut-off saws adapted to trim the opposite ends of the object turned.

A further object is to provide an improved construction and arrangement of the driving-gears for the several parts thereof by which they may be controlled from a single point in order to stop and start the same or reverse the direction of drive.

Further objects and advantages of the invention will be hereinafter set forth, and the novel features thereof defined by the appended claims.

In the drawings, Figure 1 is a front elevation of the machine with parts in section and the central portion thereof broken away. Fig. 2 is an end elevation taken at the right of Fig. 1. Fig. 3 is a similar view from the left end of Fig. 1. Fig. 4 is a detail elevation of the back cutter. Fig. 5 is a detail perspective of the reversing mechanism for the work-holder, and Fig. 6 is a detail elevation with parts in section of the driving connection for the back cutter-knife.

Like reference-letters refer to like parts in the several views of the drawings.

The letter A designates the base of the ma-

chine, which may be of any desired construction and configuration suitable for the purpose and has mounted thereon a carriage A', carrying the work-holder and the driving mechanism therefor. At suitable points a roller-bearing A² is interposed between the base and carriage and the motion of these parts equalized by means of rack-bars A³ and A⁴ upon the base and carriage, respectively, adapted to mesh with a gear-wheel A⁵, disposed between the same. The base is also provided with a standard A⁶, secured thereto at each side and provided with a nut A⁷ secured therein to feed the carriage A' by means of the screw A⁸, carried thereby and threaded into the nut. This screw at the right of the machine as shown in Fig. 2 is provided with a driving-shaft B, extended rearwardly therefrom and having thereon oppositely-disposed friction-cones B', splined thereon and adapted to coöperate with a driving-cone B², carried by a lever B³, pivotally mounted upon the base at B⁴. This lever may be operated by any desired connection. For instance, as herein shown, the lower end of the lever is provided with a slotted way B⁵, adapted to receive the eccentrically-disposed pin B⁶, carried by the pinion B⁷, mounted upon the base. This pinion is actuated from the rack-bar B⁸, extending toward the front of the machine and there connected with the operating-lever C at its lower end C'. This lever is pivotally mounted at C² upon the base, and the bar B⁸ is provided with tappets C³ thereon, by which the direction of rotation of the driving-shaft B may be automatically reversed. This reversal is accomplished by means of the fingers C⁴ and C⁵, carried by the driving-shaft and rotating therewith, as shown in Fig. 5. These fingers are adapted to coöperate with similar fingers C⁶ and C⁷, carried upon a counter-shaft C⁸, pivotally supported upon a bracket C⁹, extended forward from the base. This counter-shaft is provided with a lever D secured thereto, which is pivotally connected at its outer end with arm D' of the pivotally-mounted bell-crank lever D², the opposite arm D³ thereof being disposed between the tappets C³ upon the rack-bar B⁸. For the purpose of transferring motion from the driving-shaft B to the opposite end of the

work-holder carriage a bevel-gear D^4 is provided thereon, as shown in Fig. 1, and meshes with a similar gear D^5 , carried upon the cross-shaft D^6 . This shaft carries at its opposite end a bevel-gear D^7 , meshing with a coöperating gear D^8 , disposed upon the driving-screw A^8 , extending through the nut carried by the bracket A^6 upon that side of the machine.

10 The work-holder is composed of the head-stock E and tail-stock E' . The shaft E^2 of the head-stock is provided with a main driving-pulley E^3 , secured thereto, and with oppositely-disposed friction idler-pulleys E^4 , supported in suitable bearings carried by the carriage or by the bracket E^5 , extending laterally therefrom. This shaft at its end is provided with an adjusting-screw E^6 , mounted in a threaded bearing E^7 at the upper end 15 of the bracket E^5 and adapted to be operated by a hand-wheel E^8 and locked into position by the lock-nut E^9 , mounted on said screw. To drive the head-stock shaft, the belt F is provided and extends from the driving-pulley E^3 beneath the pulley E^4 and over the pulley F' and opposite drive-pulley F^2 upon the shaft, on which a suitable belt-pulley F^3 may be provided. (See Fig. 3.)

20 The outer end of the tail-stock spindle E' is mounted in the bracket F^4 , extended from the carriage and provided with the adjusting-pinion F^5 , mounted on screw F^6 and meshing with a similar pinion F^7 , mounted in a lateral extension F^8 from the bracket F^4 . The driving-shaft F^9 for these pinions extends rearwardly and is provided with the friction-cones F^9 , splined thereon and supported by means of brackets G' , carried by the opposite standards G , extended from the base at the rear thereof and behind the path of travel of the carriage. Coöperating with these cones is a driving-cone G^2 , carried by the lever G^3 , which is pivotally mounted at G^4 upon the standards and connected at its lower end by 25 a pivoted link G^5 to a rock-lever G^6 , pivotally mounted at G^7 and connected at its opposite end G^8 with an operating-rod G^9 , pivotally connected to the lever H at its lower end H' . Both the head and tail stocks are provided 30 with the usual chucks H^2 , adjustably mounted in bearings H^3 , constructed and supported in the usual manner so as to be moved with the carriage. The cone G^2 is driven by belt H^4 from pulley H^5 .

35 The cutter-head is rotatably supported above the work-holder by means of brackets I at opposite ends of the machine extending outward from the standards G and each provided with a slideway I' , in which the bearing-blocks I^2 are mounted, said blocks being provided with suitable bearing-boxes to receive the shaft ends I^3 of the cutter-head I^4 , as shown in Fig. 3. These bearing-blocks I^2 are adjusted vertically by means of the threaded shafts I^5 , mounted in the brackets and driven

in any suitable manner—for instance, by means of gears I^6 at their upper ends meshing with corresponding gears I^7 , carried by the cross-shaft I^8 , said shaft being extended beyond one of the bearing-boxes and there provided with a suitable operating-handle I^9 , supported in any desired manner—for instance, by the bracket I^{10} . The bearing-block is clamped in its vertically-adjusted position by means of a screw I^{11} , extending through the bracket into said block, as shown in Fig. 3. The cutter-head is driven by means of a driving-pulley J , disposed upon one end of the shaft I^8 thereof and provided with a belt J' , extending therefrom over idlers J^2 to the driving-wheel J^3 upon the shaft J^4 , mounted in suitable standards J^5 at the rear of the machine.

40 The standards G are provided with the back knife-bar K , extending between the same and carrying a plurality of blades K' , secured thereto in any desired manner and disposed in parallel planes extending diagonally to the standards with overlapping adjacent ends, so as to effect an independent cut with each 45 knife when the work-holder is brought within the path of travel thereof. This arrangement of knives obviates the long travel to produce a shearing cut extending the length of the column or other long piece of work, as a series 50 of shorter knives may be used to accomplish the same work with a short travel and in a more satisfactory manner. This bar K is adjusted to reciprocate in its motion upon the standards G by means of screws K^2 , suitably mounted therein and provided at their upper ends with a bevel-gear K^3 , meshing with a similar gear K^4 , carried by the cross-shaft K^1 , as shown in Fig. 1, this shaft being 55 also provided with oppositely-disposed friction-cones K^5 , secured thereto for the purpose of driving the same. The driving power for these cones is received from the intermediate cone K^6 , carried by a shaft K^7 , which is pivotally mounted at its lower end in a bearing K^8 and there provided with a driving-gear K^9 , adapted to mesh with a similar gear L , carried by the shaft L' , which shaft is driven by a pulley L^2 thereon, over which a driving-belt L^3 extends, as shown in Fig. 2. This 60 pulley also passes over idlers L^4 and pulley H^6 to a suitable driving-pulley L^5 upon the driving-shaft J^4 . The shaft L' also carries a pulley L^6 , from which the belt L^7 extends to drive the cone B^2 , hereinbefore described. The knife-bar carries at its upper portion the bearings L^8 , in which the shaft L^9 of the cut-off saws M is journaled. These saws are disposed at opposite ends of the machine for the purpose of cutting off the proper length of work after the turning operation has been completed and are driven in any desired manner—for instance, by means of the driving-pulley M' upon the end of the shaft L^9 , over which the belt M^2 passes, this belt being held 65

in position on opposite sides of the pulley M' by means of idlers M³, which are mounted in the frame of the saws to travel therewith in its reciprocatory movement, and thus maintain a constant driving relation between the parts. The belt M³ at its upper end passes over a suitable supporting-pulley M⁴ and at its lower end over a similar pulley M⁵. The shaft of the pulley M⁴ is extended, as shown 10 at M⁶, and there provided with a driving-pulley M⁷, to which power may be applied.

For the purpose of controlling the driving-cones for the back knife-frame and their direction of movement an operating-lever N is 15 provided at the front of the machine and pivotally connected at its lower end N' with a bar N², extending to the rear thereof, where it is pivotally connected at N³ with a bell-crank lever N⁴, the arm N⁵ of said lever being pivotally secured to the reciprocating bar N⁶, 20 mounted in suitable bearings to permit a vertical movement thereof and formed at its upper portion with rack-teeth N⁷. Meshing with these teeth is a pinion N⁸, provided with a crank-pin N⁹, extended into the slotted lower end of a pivoted lever O, the upper portion O' of said lever being connected by a link O² with the driving-shaft K⁷ of the cone K⁶, so as to shift it relatively to its co-operating cones K⁵ at each side thereof.

From the foregoing description of the several parts of the machine it will be observed that the construction and arrangement of the driving means for the several parts is such 35 that they may be controlled by a series of levers disposed at the front of the machine adjacent to the work-holder, thereby requiring the attention of but one operator after the work is placed in position. It will be seen 40 that the lever C controls the operation of the carriage supporting the work-holders, as before described, while the lever H controls the adjustment of the chuck at the tail-stock. The lever N controls the elevation and depression of the back knives and the cut-off saws carried by the frame thereof, so that 45 they may be fed up or down, as found desirable. It will be observed that the work-holder is adapted to travel laterally during 50 its rotative movement into contact with a relatively fixed rotating cutter-head which produces the most desirable results in turning columns and other large work of that character. It will also be seen that the use 55 of a plurality of knives reduces the necessary length of travel during the cut-off operation, as before described.

Having now described my invention, what I claim, and desire to secure by Letters Patent, is—

1. In a turning-lathe, a base, a carriage mounted to travel thereon, a work-holder upon said carriage, means for rotating the work by said holder during the travel of the 65 carriage, a back frame extended upward

from said base and provided with a laterally-extending bracket, a rotating cutter-head disposed in said bracket above said holder, means for automatically feeding said carriage toward and from said back frame, and means 70 for automatically reversing the direction of travel of said carriage.

2. In a turning-lathe, a work-holder, means for rotating the work therein, a rotating cutter-head disposed in a horizontal plane above 75 the holder, means for automatically feeding the work-holder transversely to its axis of rotation and beneath said head, means for reversing the direction of travel of said work-holder, means for vertically adjusting said 80 cutter-head, a frame carrying a back knife and mounted to travel in a vertical plane parallel to said cutter-head, and cut-off saws mounted upon the frame of the back knife at the opposite ends thereof.

3. In a turning-lathe, a back knife-frame mounted for reciprocation, supporting-arms carried by said frame, a shaft rotatably mounted in said arms and provided with saws at the opposite ends thereof, and means 90 for rotating said shaft.

4. In a turning-lathe, a back knife-frame mounted for reciprocation, supporting-bearings carried by said frame, a shaft rotatably mounted in said arms and provided with 95 saws at the opposite ends thereof, a driving-pulley upon said shaft, idlers at opposite sides of said pulley and carried by said frame, and a driving-belt carried by the machine-frame and disposed between said idlers and 100 driving-pulley.

5. In a turning-lathe, vertical standards, a back knife mounted to reciprocate therein, driving-screws connected to said knife, a laterally-disposed shaft extending between the 105 screws, opposite cones carried by said shaft, an intermediate driving-cone, cut-off saws supported upon the knife-frame, and a driving-belt for rotating said saws during the travel of said frame means for shifting said 110 driving-cone.

6. In a turning-lathe, vertical standards, a back knife mounted to reciprocate therein, driving-screws connected to the said knife, a laterally-disposed shaft extending between 115 the screws, opposite cones carried by said shaft, an intermediate driving-cone, a geared shaft extending from said driving-cone, means for pivotally mounting said shaft, a pivoted lever connected at its upper end to 120 said pivoted shaft, a crank-pin connected to the lower end of said lever, a gear carried by the shaft of said crank-pin, and means for operating said gear.

7. In a turning-lathe, vertical standards, a 125 back knife mounted to reciprocate therein, driving-screws connected to said knife, a laterally-disposed shaft extending between the screws, opposite cones carried by said shaft, an intermediate driving-cone, a geared shaft 130

extending from said driving-cone, means for pivotally mounting said shaft, a pivoted lever connected at its upper end to said pivoted shaft, a crank-pin connected to the lower end of said lever, a gear carried by the shaft of said crank-pin, a reciprocating rack meshing with said gear, a controlling-lever pivotally mounted upon the base of the machine, and connections extending between said controlling-lever and rack to reciprocate the latter.

8. In a turning-lathe, a base, a carriage mounted to travel thereon, a rotatable work-holder mounted upon said carriage, a driving-shaft extending from and movable with said carriage, oppositely-disposed cones splined upon said shaft and supported against longitudinal movement therewith, an intermediate driving-cone, a pivoted lever carrying said driving-cone at one end, tappets carried by said driving-shaft, and means extending from said lever and disposed in the path of said tappets to be actuated thereby.

9. In a turning-lathe, a base, a carriage mounted to travel thereon, a work-holder mounted upon said carriage, means for rotating said work-holder a standard carried by the base and provided with a nut mounted therein, a driving-screw carried by said carriage, a driving-shaft extending from said screw and provided with opposite cones thereon, an intermediate driving-cone mounted upon a pivoted lever, a controlling-lever mounted upon the base and provided with a rack-bar connected therewith, a gear mounted upon the base and meshing with said bar, and a crank-pin carried by said gear to engage a slotted end of said lever.

10. In a turning-lathe, a base, a carriage mounted to travel thereon, a work-holder mounted upon said carriage, means for rotating said work-holder a standard carried by the base and provided with a nut mounted therein, a driving-screw carried by said carriage, a driving-shaft extending from said screw and provided with opposite cones thereon, an intermediate driving-cone mounted upon a pivoted lever, a controlling-lever mounted upon the base and provided with a rack-bar connected therewith, a gear mounted upon the base and meshing with said bar, a crank-pin carried by said gear to engage a slotted end of said lever, fingers carried by said driving-shaft, a counter-shaft provided with cooperating fingers, a lever extending from said counter-shaft, and a bell-crank lever pivotally connected to said counter-shaft lever and having its opposite end disposed in the path of tappets carried by said rack-bar.

11. In a turning-lathe, a stock provided with a driving-gear thereon, a chuck-spindle carried by said stock and longitudinally adjusted by said gear, a driving-shaft having a pinion coöperating with said gear, means for

producing a travel of said stock laterally of the spindle, opposite cones splined upon said shaft, and an intermediate driving-cone.

12. In a turning-lathe, a stock provided with a driving-gear thereon, a chuck-spindle carried by said stock and longitudinally adjusted by said gear, a driving-shaft having a pinion coöperating with said gear, means for producing a travel of said stock laterally of the spindle, opposite cones splined upon said shaft, an intermediate driving-cone, a pivoted lever carrying said driving-cone at one end, a controlling-lever mounted upon the base, and connections extending from said controlling-lever to said pivoted lever for shifting the same.

13. In a turning-lathe, a carriage, means for driving the same, a work-holder mounted upon said carriage, means for adjusting the chuck of said work-holder, controlling-levers mounted upon a common pivot and provided with connections to the carriage-driving and work-holder-chuck-adjusting shafts respectively, and means controlled by the carriage-driving shaft for automatically reversing the travel thereof and shifting its controlling-lever.

14. In a turning-lathe, a carriage, means for driving the same, a work-holder mounted upon said carriage, means for adjusting the chuck of said work-holder, controlling-levers mounted upon a common pivot and provided with connections to the carriage-driving and work-holder-chuck-adjusting shafts respectively, means controlled by the carriage-driving shaft for automatically reversing the travel thereof and shifting its controller-lever, a back knife, driving means for reciprocating the same, and a controlling-lever for said driving means mounted upon a common pivot with the before-mentioned controlling-levers.

15. In a turning-lathe, a carriage, means for driving the same, a work-holder mounted upon said carriage, means for adjusting the chuck of said work-holder, controlling-levers mounted upon a common pivot and provided with connections to the carriage-driving and work-holder-chuck-adjusting shafts respectively, means controlled by the carriage-driving shaft for automatically reversing the travel thereof and shifting its controlling-lever, a back knife, driving means for reciprocating the same, a controlling-lever for said driving means mounted upon a common pivot with the before-mentioned controlling-levers, cut-off saws supported upon the frame of said knife, and means for continuously driving said saws during the movement of the knife-frame.

16. In a turning-lathe, a carriage, means for driving the same, a work-holder mounted upon said carriage, means for adjusting the chuck of said work-holder, controlling-levers mounted upon a common frame and pro-

vided with connections to the carriage-driving and work-holder-chuck-adjusting shafts respectively, means controlled by the carriage-driving shaft for automatically reversing the travel thereof and shifting the controlling-lever, a back knife, driving means for reciprocating the same, a controlling-lever for said driving means mounted upon a common pivot with the before-mentioned controlling-levers, cut-off saws supported upon the frame of the knife, means for continu-

ously driving said saws during the movement of the knife-frame, a rotatable cutter-head, means for continuously driving the same, and means for vertically adjusting said head 15 while being driven.

In testimony whereof I affix my signature in presence of two witnesses.

FREDRICK NEUDORFF.
